FLEXIBLY MOUNTED MAIL BOX

James W. Goss, Warren, Ohio

Application February 7, 1956, Serial No. 563,899

2 Claims. (Cl. 248—160)

The invention relates to mountings for mail boxes and the like, and more particularly to a flexible mounting for a rural mail box which permits rotary movement of the box upon the post and swinging movement of the post either laterally or longitudinally of the road or highway along which the box is located, in the event that the mail box or post on which it is mounted is struck by a passing vehicle.

In suburban and rural areas where it is customary to mount mail boxes on posts located at the side of the road or highway, considerable difficulty is experienced by the owners of such mail boxes, due to passing vehicles striking either the mail box or the post on which it is mounted, resulting in damage to the mail box, or breaking of the post, or both.

The present invention contemplates a flexible mounting for such mail boxes which will eliminate the above-mentioned difficulties and the consequent annoyance and expense to the owners thereof. This flexible mounting includes a frictional vertical pivotal connection between the mail box and the top of the post, whereby the mail box is permitted to turn upon its pivot when struck by a passing vehicle or the like, thus preventing the mail box from being seriously damaged or broken loose from the supporting post.

Further, the flexible mounting includes frictional horizontal pivotal connections in the post, on axes at right angles to each other, whereby the post may swing upon its pivots, either longitudinally or laterally of the road, depending upon the direction in which it may be struck.

It is therefore an object of the invention to provide a flexible mounting for a mail box which overcomes the above difficulties.

Another object is to provide a mail box vertically frictionally pivoted upon the supporting post, whereby it may be swung around the pivot point, without serious damage to the mail box or post, in the event a passing vehicle strikes the mail box.

A further object is to provide such a mail box mounting in which the supporting post is provided with a horizontal frictional pivot located at right angles to the road, whereby the post may swing forwardly upon its pivot if struck by a vehicle passing along the road.

A still further object is to provide a mail box mounting of this type in which a horizontal frictional pivot is located in the mounting post, in a plane parallel to the road, whereby the post may swing inwardly away from the road if struck by a vehicle turning or backing across the road.

The above objects together with others which will be apparent from the drawing and following description, or which may be later referred to, may be attained by constructing the flexible mounting in the manner hereinafter described in detail and illustrated in the accompanying drawing, in which:

Fig. 1 is an elevation of a mail box mounted upon a post embodying the invention, as viewed from a road along which it is located;

2

Fig. 2 is an enlarged, transverse sectional view through one of the pivot joints of the post, taken on the line 2—2, Fig. 1; and,

Fig. 3 is a similar section through the other pivot joint 5 of the post, taken on the line 3—3, Fig. 1.

Referring now more particularly to the embodiment of the invention illustrated in the drawing, in which similar numerals refer to similar parts throughout, the improved flexible mounting includes a fixed or rigid post 10, embedded in the ground as shown in Fig. 1, with only a few inches thereof extending above the ground line indicated at G.

The post 10 is preferably formed of metal, and may be of the cross-sectional shape best shown in Fig. 3, 15 comprising the substantially semi-circular portion 11 with out-turned flanges 12 at its edges. For the purpose of providing a horizontal pivot parallel to the road along which the mail box is located, a flat plate 13 is located across the open side of the post 10, the edges thereof 20 being welded to the flanges 12 of the post 10, as at 14.

A bolt 15 is located through a suitable centrally located aperture in the plate 13, and through the pivoted post section indicated generally at 16, which may be in the form of a square tube, as best shown in Figs. 2 and 3. 25 A spacer washer 17 is interposed between the plate 13 and the tubular pivoted member 16, and nuts 18 and 19 are located upon the outer end of the bolt 15.

In adjusting the parts above described, the nut 18 is tightened sufficiently to frictionally hold the tubular pivoted member normally in vertical position, while permitting the same to pivot upon the bolt 15 in the event of impact by a vehicle or the like, in a direction laterally of the road. The locking nut 19 is then tightened to hold the nut 18 in adjusted position.

30 The upper pivoted section 20 of the post is flexibly connected to the tubular pivoted section 16, upon a horizontal frictional pivot located at right angles to the pivot bolt 15, whereby the same may swing in a plane parallel to the road. This section 20 of the post may be of the same cross-sectional shape as the fixed post section 10, 35 and has a flat plate 21 welded across the open side thereof.

The pivot bolt 22 is located through the upper portion 40 of the pivoted tubular member 16 and through the plate 21, a washer 23 being interposed therebetween. The nut 24 is tightened upon the end of the bolt 22, sufficiently to frictionally hold the post section 20 normally in upright position while permitting the same to pivot upon the bolt 22 in event it is struck by a passing vehicle. 50 The nut 24 is held in adjusted position by the locking nut 25.

At the top of the section 20 of the post, a flat plate 26 is welded thereto. The mail box, indicated generally 55 at 27, may be any conventional construction of rural mail box, and for the purpose of the invention, a plate 28 is attached to the lower side thereof, to receive the vertical pivot bolt 29.

This bolt is located through suitable apertures in the 60 plates 26 and 28, a spacer washer 30 being interposed therebetween. A nut 31 is tightened upon the end of the bolt 29 sufficiently to normally frictionally hold the mail box in position laterally of the road, but permitting the mail box to swing around the bolt 29 in the event it is 65 struck by a passing vehicle, and is locked by nut 32.

From the above it will be obvious that the flexible mounting protects both the mail box and the post from breakage or serious damage if either the box or the post is struck by a vehicle. If the end portion of the 70 box nearest to the road is struck by a passing vehicle, the flexible pivot 29 will permit the box to swing around the pivot in a horizontal plane without serious damage

to the box and without breaking it loose from the post.

Should a vehicle passing along the road strike the upper pivotal section 20 of the post, it will merely cause the same to swing upon the horizontal pivot 22, without serious damage to the post or box.

In the same manner, if the post is struck by a car moving laterally across the road, the sections 16 and 20 of the post will swing upon the horizontal pivot point 15, outward away from the road.

It should be understood that after the mail box, or either section of the post, has been swung upon its pivot, the parts will remain in this position until they are manually adjusted to the normal position again. Although the invention is primarily adapted for mounting mail boxes, it may also be applied to signs or other devices which may be mounted upon a post along a highway or the like.

Further, it is pointed out that, if desired, the post may comprise only one pivoted section, pivoted to the stationary lower section of the post on a horizontal pivot disposed laterally of the road, so that the pivoted section of the post may swing forwardly if struck by a passing vehicle.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

Having now described the invention or discovery, the construction, the operation, and use of preferred embodiments thereof, and the advantageous new and useful results obtained thereby; the new and useful construction, and reasonable mechanical equivalents thereof obvious to those skilled in the art, are set forth in the appended claims.

I claim:

1. A flexible mounting for a mail box and the like, comprising a stationary lower post section, a pivoted intermediate post section, a horizontally disposed pivot bolt located through the upper end of the stationary post section and the lower end of the intermediate post section, a spacer washer on said bolt between said post sections, an adjusting nut for adjusting tension upon said bolt for frictionally pivoting said pivoted post section upon the stationary post section so as to normally hold the pivoted post section in upright position while permitting it to be swung upon its pivot under impact and to hold the pivoted post section in any position to which it may be swung, a lock nut for holding the adjusting nut in adjusted position, a pivoted upper post section, a second horizontal pivot bolt disposed at right angles to the first named pivot bolt and located through the upper end of the intermediate post section and the lower end of the upper post section, a spacer washer on said second pivot bolt between the intermediate post section and the upper post section, an adjusting nut for adjusting tension upon said second bolt for frictionally piv-

oting said upper post section upon the intermediate post section so as to normally hold the upper post section in upright position while permitting it to be swung upon its pivot under impact and to hold said upper post section in any position to which it may be swung, a lock nut for holding the second named adjusting nut in adjusted position, a horizontal plate fixed to the top of the upper post section, a mail box, a second horizontal plate fixed to the bottom of the mail box, a vertical pivot bolt located through said horizontal plates, a spacer washer on the vertical bolt between said horizontal plates, an adjusting nut for frictionally pivoting the mail box so as to normally hold the mail box in any adjusted position while permitting it to be swung upon its pivot under impact and to hold the mail box in any position to which it may be swung, and a lock nut for holding the adjusting nut upon said vertical bolt in adjusted position, whereby the intermediate post section, the upper post section and the mail box are each held in adjusted position and each may be swung upon its pivot by impact and held in any position to which it may be swung.

2. A flexible mounting for a mail box and the like, comprising a stationary lower post section, a pivoted intermediate post section, a horizontally disposed pivot bolt located through the upper end of the stationary post section and the lower end of the intermediate post section, a spacer washer on said bolt between said post sections, an adjusting nut for adjusting tension upon said bolt for frictionally pivoting said pivoted post section upon the stationary post section so as to normally hold the pivoted post section in upright position while permitting it to be swung upon its pivot under impact and to hold the pivoted post section in any position to which it may be swung, a lock nut for holding the adjusting nut in adjusted position, a pivoted upper post section, a second horizontal pivot bolt disposed at right angles to the first named pivot bolt and located through the upper end of the intermediate post section and the lower end of the upper post section, a spacer washer on said second pivot bolt between the intermediate post section and the upper post section, an adjusting nut for adjusting tension upon said second bolt for frictionally pivoting said upper post section upon the intermediate post section so as to normally hold the upper post section in upright position while permitting it to be swung upon its pivot under impact and to hold said upper post section in any position to which it may be swung, and a lock nut for holding the second named adjusting nut in adjusted position, whereby the intermediate post section and the upper post section are each held in adjusted position and each may be swung upon its pivot by impact and held in any position to which it may be swung.
